RELAY TUBE

Harvey C. Rentschler, East Orange, N. J., assignor, by mesne assignments, to Westinghouse Electric and Manufacturing Company, East Pittsburgh, Pa., a corporation of Pennsylvania

Application May 1, 1934, Serial No. 723,311

2 Claims. (Cl. 250—27.5)

This invention relates to an electric discharge device of the gaseous conduction type. In its more specific aspect the invention is directed to an improved relay tube having cold electrodes between which a discharge may take place.

In Patent No. 1,875,151 issued to me on August 30, 1932, there is described and claimed a glow relay tube of the type with which this invention is concerned. The tube described in said patent comprises an envelope containing a cathode, a starting anode and a main or service anode. A small projection or starting tip extends from the cathode and terminates adjacent the starting anode. The cathode is of cylindrical form and surrounds both the main and starting anodes. The envelope also contains a rare gas such as argon at a pressure of about 5 to 8 millimeters.

In the course of my experimentations with tubes of this character and especially when employing the same in the circuit set forth in my patent application Serial No. 328,243 filed on December 24, 1928, now Patent No. 2,037,924, dated April 21, 1936, and assigned to the same assignee as the present invention, I have found that improved and more constant results may be obtained with tubes containing the improvements of the present invention.

Briefly my invention contemplates the employment of relatively small electrodes, a relatively "high" gas pressure and one or more electrodes surfaced with a substance such as thorium having a low voltage drop at the surface thereof. The envelope of the tube should be composed of a dielectric as for example Pyrex or other glass having a low surface leakage characteristic when in an atmosphere of high humidity.

An object of my invention is to provide a relay tube having improved and constant electrical characteristics.

Another object of my invention is to provide a simple glow relay tube of the three electrode and gaseous conduction type in which a predetermined discharge initiated between two of said electrodes is always sufficient to cause initiation between two main electrodes when a predetermined potential is applied between the two main electrodes.

These and other objects of my invention will be readily apparent from the following description and drawing wherein,

Figure 1 represents a view in elevation, with part of the envelope broken away, of a tube embodying my invention;

Figure 2 represents a view similar to Figure 1

and taken at ninety degrees to view illustrated in Figure 1; and

Figure 3 represents a cross sectional view, on line III—III of Figure 1, in the direction of the arrows.

As shown in the drawing, my improved tube comprises an envelope 19 having a press 11 in which are sealed lead-in conductors 12 and 13 extending interiorly and exteriorly of said envelope and connected to suitable contact pins 10 15 carried by a base 16. Although but two contact pins 15 are indispensable, I prefer to employ four contact pins with two of them being dummies.

The upper portions 17 and 19 of the lead-in conductors 12 and 13 and the lower portion of the support 18 are embedded in the press 11 and supported thereby. The conductors 17 and 18 are located at the ends of the press and the conductor 19 is between conductors 17 and 18. The conductor 19 extends slightly upwardly, then outwardly and then upwardly and substantially parallel to the conductors 17 and 18. The conductor 18 is a dummy support wire terminating in the press. All of the conductors have the major portion thereof composed of nickel.

Respectively carried by supports 17, 18 and 19 are cylindrical rods 20, 21 and 22, with rod 21 being the starting anode, rod 22 the cathode, and rod 20, the main anode. These rods 20, 21 and 22 are about 150 mils in diameter and about $\frac{3}{8}$ of an inch in length and are clamped, or by other appropriate means, secured to short nickel rods welded to the supports 17, 18 and 19. The thorium electrodes 20, 21 and 22 are so arranged that they are parallel and adjacent to each other, with the rods 21 and 22 spaced about one millimeter apart and the rods 20 and 22 spaced about three millimeters apart.

The cathode is located off the line of the press and between the anodes 20 and 21 so that when ionization occurs between the starting anode 21 and the cathode 22, ionized gas is directly in the vicinity of the space between the cathode 22 and anode 20 so that a discharge may readily occur therebetween. Glass rods 23 surround the supports 17 and 18 along the major portion of the lengths thereof. These rods 23 are sealed to the press 11 and serve to prevent discharge and electrical leakage between the supporting posts for the electrodes. A lead-in conductor 24, electrically connected to a contact cap 25, is electrically connected to the starting anode 21.

The contact cap 25 is located at the uppermost part of the envelope and thus is remotely dis-

posed from the contact pins 15, so that leakage along the envelope shall be inappreciable. In order to further enhance the usefulness of this tube as a relay device in my circuit hereinbefore referred to, the envelope is composed of a glass having a low electrical leakage characteristic, especially when in an atmosphere of high humidity. For this purpose I prefer to employ Pyrex or other type of glass having said property.

10 One other improvement that I have made in the present invention is to employ a rare gas such as argon within the envelope at a pressure of about 20 to 50 millimeters of mercury, and preferably between 30 and 35 millimeters of mercury.

15 With a tube of the character above described, it is possible to apply a potential, between the main anode 20 and the cathode 22, insufficient to normally cause breakdown or a discharge therebetween. Upon a predetermined potential being applied between said cathode 22 and starting anode 21, a discharge occurs therebetween to ionize the gas within the envelope and in the vicinity of the space between the main anode 20 and cathode 22. Due to this ionization of the 25 gas, the resistance of the path is reduced between the main anode 20 and the cathode 22, so that the potential applied thereacross is now sufficient to cause breakdown therebetween. The improved tube which I have described is constant 30 in operation.

Although I have described the invention with some particularity, it is not to be limited thereby, but only by the prior art.

What is claimed:

1. A relay tube of the gaseous conduction type comprising an envelope having a press, a plurality of supports sealed in said press, a plurality of electrodes within said envelope comprising a main anode, a starting anode and a cathode secured to said supports, said electrodes being of cylindrical form and having their longitudinal axes in substantial parallelism and bodily spaced apart, and a rare gas within said envelope, said starting anode and cathode being spaced a distance of about one millimeter and said main anode and cathode being spaced a distance approximately three times the distance between said starting anode and cathode, the gas in said envelope being at a pressure between twenty and fifty millimeters of mercury.

2. A relay tube comprising an envelope enclosing a press, a plurality of supports extending from said press, a plurality of electrodes secured to said supports, said electrodes including a main anode, a starting anode, and a cathode, all of said electrodes being formed of thorium, cylindrical in form, having their longitudinal axes substantially parallel, and spaced apart bodily, and argon at a pressure of from about 30 to 35 m. m. of mercury enclosed in said envelope, said starting anode and cathode being spaced apart a distance of about 1 m. m., and said main anode and cathode being spaced apart a distance of about 3 m. m.
